TYPEWRITING MACHINE

William F. Helmond, West Hartford, Conn., assignor to Underwood Elliott Fisher Company, New York, N. Y., a corporation of Delaware

Application June 22, 1939, Serial No. 280,544

5 Claims. (Cl. 197—74)

This invention relates to typewriting machines, and, with regard to certain more specific features thereof, to case-shifting devices particularly of the character in which electromagnetic or other power drive agencies are employed in the operation of shifting from one case typing position to another.

The invention has for one of its objects to provide a case-shifting mechanism which shall be simple in construction, inexpensive, reliably operative, harmonic, extremely speedy in operation, and in which there shall be a marked reduction in noise.

It is another object of the invention to employ a continuously operating power-driven shaft and to control by manipulation of a single key the coupling and uncoupling of the power-driven shaft with the member to be shifted, in such manner that continued rotation of the power-driven shaft in one direction may be utilized for power shifting the part successively in opposite directions and so controlling the shifting movements that the part is brought to its opposite extremes of movement positively and quickly under definite control and without the use of any slip friction device.

It is a further object of the invention to drive the part to be shifted in one or both directions in a positive manner from a power-driven toothed roller without backlash or rebound when the part reaches its limit of movement.

Other objects will be in part obvious and in part pointed out particularly as the following description of a preferred embodiment of the invention proceeds.

The invention, accordingly, consists in the various features of construction, combination of elements, and arrangements of parts which will be exemplified by the following description and the accompanying drawings, and the scope of the application of which will be indicated in the appended claims.

In the drawings:

Fig. 1 is a view in left side elevation of a typewriter embodying the invention. The parts are shown in the positions which they occupy in the normal or lower-case typing position.

Fig. 2 is a view of the case-shifting mechanism shown in Fig. 1 but with the parts in the positions which they occupy when the case-shift key has been depressed to allow the power agencies to shift the type-bar segment to so-called upper-case typing position.

Fig. 3 is a view of the mechanism shown in Figs. 1 and 2 but with the parts in the positions

which they assume when the type-bar segment has been shifted for upper-case typing and the case-shift lock key has been depressed to lock the segment in upper-case position.

Fig. 4 is a skeletonized perspective showing the case-shift mechanism illustrated in Figs. 1 to 3.

Fig. 5 is a sub-assembly view showing the limiting stops for the case-shifting movement.

Fig. 6 is a sectional view taken substantially along the line 6—6 of Fig. 1.

Fig. 7 is a perspective view of the eccentric and ball bearing mounted strap utilized in carrying out the invention.

Fig. 8 is a view of the parts shown in Fig. 7 taken from the reverse side of the assembly.

Referring now more in detail to the drawings, a typewriter frame is indicated generally at 10. It has conventional side walls 11 within which is journaled a drive shaft 12 in the form of a toothed or fluted roller which is driven from any suitable source of power such as an electric motor (not shown in the drawings). Preferably, the drive shaft is continuously rotated while the typewriter is being used and the various functions of the typewriter are performed by transitory coupling of their mechanisms with the drive shaft.

In the embodiment of the invention presently described, case-shifting is effected by movement of the type carrying segment shown in Fig. 4 at 13, but it is to be understood that the invention, in certain of its aspects, is applicable as well to typewriters in which the platen is shifted. In the present case the main frame of the typewriter is provided with vertical uprights one of which is shown in Fig. 4 of the drawings at 14. Ball bearing raceways are provided in the uprights for slidably receiving a segment mounting 15 which at opposite sides has pivotal connection at 16 with arms 17 extending rearwardly from a rock-shaft 18 pivoted in the side walls of the typewriter at 19. Counterbalance springs 20 urge the segment mounting to normal or lower-case typing position. A suitable type-bar rest 21 is provided for nesting the type-bars in their rest or inoperative positions. The rest 21 is secured to the segment mounting so as to be movable with it in its sliding movement to different case positions.

Pivots 16 are formed by studs 22, the one at the left side of the machine being embraced by a rockable yoke 23 movable around pivot 19. The yoke has outwardly extending opposed upper and lower flanges 24 and 25 respectively through

which adjustment screws 26 and 27 extend. These screws confine the stud 22 at the left side of the machine so that rocking movement of yoke 23 will move the segment mounting 15 up and down in the uprights or sideways 14. The lower side of yoke 23 is connected to a strap 28 which surrounds an eccentric 30, these members being provided with inner and outer ball-races respectively for the reception of ball-bearing elements 31. The eccentric is reduced in thickness at 32 and is penetrated at its reduced portion by a reduced portion 33 at the end of the drive shaft 12. The drive shaft portion 33 is journaled in a bushing 34 secured to the inner side of the side wall 11 on the typewriter frame and passes outwardly through a detent or backlash preventing member 35 pinned, brazed, or otherwise suitably secured to the eccentric 30. Portion 33 passes further through the reduced portion 32 of the eccentric and on its end has fixed for rotation therewith a clutch wheel 36 having teeth corresponding in number and position to the teeth on drive shaft 12. Clutch wheel 36 is thus continuously driven with the drive shaft 12 and may be transitorily connected with the eccentric 30 by a clutch member or dog 37 pivotally mounted on the eccentric at 38 and normally urged by a spring-pressed plunger 40 in the eccentric, bearing against a tail 41 of the dog, in a direction to engage the clutch wheel 36.

When the mechanism is in lower-case typing position, as shown in Figs. 1 and 4 of the drawings, pivoted dog 37 is held out of engagement with the clutch wheel by a lever 42, the end 43 of which has been swung into position to intercept a tail 44 on dog 37 and move it pivotally until its tail 41 has compressed spring 40 and abutted the bottom of a slot 45 in the eccentric 30. Lever 42 is pivoted at 46 in a plate 47 secured to the outer side of side wall 11. A lever 48 is also pivoted on this plate as indicated at 50 and corresponding ends of levers 42 and 48 are connected by a link 51 for parallel motion.

Lever 42 has an ear 52 pivoted at 53 to a link 54, the forward end of which is pivoted at 55 to an arm 56 fixed on a shaft 57. Forwardly of the typewriter frame an angle-shaped comb-plate 58 is secured between the side walls 11. Brackets 60 riveted to opposite ends of the angle-plate provide ears 61 which journal shaft 57, the latter being held against lateral displacement by a screw 62 at the right end of the shaft. Welded or otherwise secured to the shaft 57 near opposite ends are the case-shift key-levers 63 and 64 having respectively keys 65 and 66. A coil spring 67 having one end anchored to a side wall 11 at 68 and the other end connected to arm 56 at 70 normally holds the case-shift key-levers in their upper normal or lower-case typing positions, thus also keeping lever 52 with its end 43 engaging tail 44 of the pivoted clutch dog 37 maintaining a disengaged relation of the clutch parts.

As either of the keys 65 and 66 is depressed, shaft 57 will be rocked moving arm 56 and link 54 forwardly thus releasing lever 52 from the tail of the pivoted clutch dog, whereupon spring-pressed plunger 40 urges the dog into engagement with one of the teeth of the continuously rotating clutch wheel 36. At the same time that lever 42 is swung on its pivot, by depression of the case-shift key, lever 48 is swung about its pivot 50 into the position shown in Fig. 3 of the drawings, where a hook 71 on the end of lever

48 lies in the path of tail 44 of the pivoted clutch dog so as to remove the dog from its clutching engagement after a rotary movement of its pivot amounting to 180 degrees. This results in a part rotation of eccentric 30 and a lineal movement of strap 28 which rocks the yoke 23 and depresses the segment mounting and the entire type basket to an upper-case typing position determined by adjustable stops at opposite sides 10 of the machine.

The position-limiting stops are shown in Fig. 5 of the drawings and comprise shackles 72 fixed against the inner surfaces of the opposite side walls 11 of the frame. Each shackle confines one end of a pack of loose metal strips 73, the opposite ends of which are backed up against the ends of adjustment screws 74 threaded into ears 15 projecting inwardly from the side walls of the frame. As the segment mounting is moved from one case position to another, opposite end studs 22 engage the strip packs compressing them from loose fanned condition to substantially solid packs backed up by screws 74. The eccentric and strap device provides a substantially definite control for the movement of yoke 23 and has the effect of shifting studs 22 quickly from one position to another and terminating with a deceleration in the rate of movement which brings the studs quickly into contact with the packs in their fanned condition and the squeezing of the laminations into tightly compressed packs backed up by the adjustment screws. This construction tends to greatly reduce the noise and shock of impact as the air between each lamination is forced out in the compressing of the pack.

As the operator releases the case-shift key, spring 67 becomes effective to move the levers 42 and 48 in parallelism in the opposite direction, thus releasing hook 71 from the tail of clutch dog 37 allowing the dog to reengage the clutch wheel 36 and thus the eccentric is again moved 40 180 degrees in the same direction of rotation until tail 44 of the clutch dog is intercepted by end 43 of lever 42 and the clutch engagement is again broken. In this operation the segment is raised to normal or lower-case typing position and spring 67 maintains the clutch disengaged until one of the case-shift lever keys is again depressed.

To insure against rebound or reverse rotation of the eccentric in the operation of the mechanism just described, a bell-crank lever 76 is pivotally mounted on the left side wall 11 of the frame at 77. A downwardly extending arm 78 of the lever is connected by a spring 80 under some tension to the side wall. A detent nose 81 of the bell-crank lever rides upon the cam-shaped member 35 which, as previously stated, is secured to the eccentric 30, and fits into peripheral depressions 82 and 83 as the eccentric is released after its 180 degree movements, by disengagement of the clutch.

The case-shift key-lever may be held depressed and the segment consequently maintained for repeated typing operations in its upper-case typing position by a shift-lock mechanism comprising a key-lock-lever 84. In the embodiment shown there is one of these shift lock mechanisms for each of the key levers 63 and 64, but as they are substantially identical a description of one will suffice. The key-lock lever is pivoted at 85 on the case-shift key-lever 63. Also pivoted on the case-shift key-lever at 86 is a latch element 87 having an upwardly extending arm 88 with a

latch face 90. The latch element has oppositely extending arms 91 and 92 below its pivot 86, which arms rest in an aperture 93 provided by the lever 84. An operating finger 94 on lever 84 overlies the arm 92 of the latch element and as a key 95 of lever 84 is depressed around its pivot 85 finger 94 bearing against arm 92 swings the latch element clockwise, as viewed in the drawings, against the action of return spring 96 until latch face 90 is deposited under a lug 97 extending from the angle member 58. Release of the keys with the parts in this position allows spring 67 to exert sufficient pressure to hold the keys in their latched-down position. Thereafter depression of the case-shift key will slightly separate latch face 90 from lug 97 allowing spring 96 to restore the latch part and the lever 84 and case-shift key-lever 63 may then rise under the action of spring 67. The latch element is also provided with an offset finger 98 which parallels and confines operating finger 94 between the case-shift key-lever and finger 96 in position to overlie arm 92 of the latch element.

The ball bearing between the eccentric and its strap reduces friction and also allows just sufficient looseness to nicely accommodate the device to the squeezing action hereinbefore described in respect to the laminated stops. Proper setting of the adjustment screws 74 will result in the shift being made to both case positions accurately and noiselessly. As the shift from one case position to another is in consequence of continued movement of the eccentric in the same direction, no dead center problems are involved and the movement is particularly easy, quick and positive, and especially suitable for case-shift operation in both directions under power.

The segment 18, of course, carries the usual arcuate fulcrum wire 100 upon which type-bars 181 are mounted to move within slots 102.

What is claimed is:

1. In a typewriter, a case-shift device comprising, a part to be shifted, continuously rotating means including a toothed clutch element, cam means normally quiescent and including a companion clutch element, means connecting the cam means and the part to be shifted having provision whereby rotation of said cam means causes a reciprocatory movement of the said part, and means for controlling the rotation of the cam means having provision for engaging said clutch elements, breaking the engagement upon partial rotation of the cam means, reestablishing the engagement for continued rotation of the cam means and rebreaking the engagement when full rotation has been effected.

2. In a typewriter, a case-shift mechanism comprising, a part to be shifted, a rotating drive-

shaft, an eccentric loose on the shaft, a clutch element fixed on the shaft, a companion clutch element on the eccentric, connections from the eccentric to the part to be shifted for transmitting motion to the part positively in opposite directions as the eccentric moves through a complete rotation, a case-shift key, and means responsive to one movement of said key to effect engagement of the clutch elements to rotate the eccentric a partial rotation with the drive shaft and effect disengagement of the clutch elements at the end of said partial rotation, said means being responsive to another movement of the key to effect reengagement of the clutch elements to continue the rotation of the eccentric in the same direction until it has made a complete rotation and to effect disengagement of the clutch elements at the end of the complete rotation.

3. In a typewriter, a case-shift device comprising, a part to be shifted, a continuously rotating drive-shaft, an eccentric loose on said drive-shaft, a toothed clutch wheel fixed on said drive-shaft, a clutch dog pivotally mounted on said eccentric and spring-urged toward a position of engagement with the clutch wheel, a strap around said eccentric, a rocker embracing the part to be shifted and pivotally connected to the strap, a key-controlled parallel-link mechanism normally holding the clutch dog disengaged and having provision for releasing the dog upon depression of the key and disengaging it at the end of a partial rotation of the eccentric, and having provision for again releasing the dog upon return of the key and again disengaging it upon the completion of rotation of the eccentric.

4. In a typewriter, a case-shift device comprising, a type bar segment, means mounting the segment for shifting movement, continuously rotating means, an eccentric, key-controlled clutch means for transiently coupling the eccentric to the rotating means, a strap having an anti-friction bearing around the eccentric, and a rockable member pivotally connected to the strap and embracing the mounting means for the segment.

5. In a typewriter, a case shift mechanism comprising a shaft having end bearings and arms at opposite ends, a segment-mount pivotally connected to said arms, a rocker member engaging the segment-mount and having its rocking axis in line with said shaft, an eccentric, a strap on said eccentric connecting with said rocker member, a drive shaft, and means for transiently coupling the eccentric and drive shaft for part rotations of the eccentric each of which moves the segment-mount in an opposite direction.

WILLIAM F. HELMOND.
